UNITED STATES PATENT OFFICE.

ALEXANDER DUDGEON, OF CALEDONIAN ROAD, MIDDLESEX COUNTY,
GREAT BRITAIN.

STEAM-PACKING.

SPECIFICATION forming part of Letters Patent No. 232,011, dated September 7, 1880.

Application filed March 12, 1879.

To all whom it may concern:

Be it known that I, ALEXANDER DUDGEON, of Caledonian Road, in the county of Middlesex, Kingdom of Great Britain and Ireland, have invented new and useful Improvements 5 in the Manufacture of Packing for Parts of Steam-Engines and for other Uses, of which the following is a specification.

In order to produce an efficient and a durable 10 packing for parts of steam and other engines, &c., I use asbestos in sheets, formed in a similar manner to asbestos paper, and I fix the said asbestos sheet in strips of suitable widths short distances apart on canvas made of cotton, flax, hemp, or other cloths, so that when 15 the canvas is rolled up with a solution of india-rubber a succession of bags is formed, wherein the sheets of asbestos are confined, thus preventing waste of asbestos, which cannot 20 escape into the gland until the outside layer of canvas is worn through. Thus the successive layers of asbestos in the bags are 25 successively brought into contact with the piston or other rod or moving part of the machine as the packing wears.

Packing as described may be steeped in a 30 solution of silicate of soda, silicate of potash, stannate of soda, or other substances containing properties to resist the action of great heat, or in paraffine or other lubricating substances.

The core consists of a strip of vulcanized india-rubber.

Referring to the accompanying sheet of drawings, Figure 1 shows in plan, and Fig. 2

in section, a piece of canvas, *a*, onto which is 35 fastened a core consisting of a strip of vulcanized india-rubber or of alternate strips *b* *b'*, also a sheet of asbestos, *c*. Having fastened the compound core and the asbestos onto the canvas, I next coat the surface (shown in 40 Fig. 1) with a solution of india-rubber, and I then roll the canvas with its superposed asbestos around the core, after which the compound body may be pressed into any convenient sectional form. (See Figs. 3, 4, and 7.) 45

Figs. 5 and 6 are corresponding views to 50 Figs. 1 and 2, showing the mode of making the packing with a number of strips, *c*, of asbestos sheet, the process of manufacture being the same.

Figs. 8 and 9 show how the packing is made 55 with diagonal strips of asbestos sheet *c*, and Figs. 10 and 11 show the packing made with plaited or woven vegetable fiber *a* in lieu of canvas. *b* is the core as before, and *c* the other asbestos sheet.

What I claim is—

The packing described, having a core of rubber, around which are wound layers of canvas and asbestos cemented with rubber, as 60 herein specified.

ALEXANDER DUDGEON.
